Specification for Design.

Patented Nov. 5, 1907

Application filed September 12, 1907. Serial No. 392,598. Term of patent 7 years.

To all whom it may concern:

Be it known that I, ALFRED JOHN MEAKIN, a subject of the King of England, and a resident of Tunstall, Staffordshire, England, have invented a certain new, original, and ornamental Design for a Covered Dish or Similar Article, of which the following is a specification.

In the accompanying drawing, Figure 1 is a side elevation showing the design of the covered dish. Fig. 2 is a plan of the same.

What I claim is:—

The ornamental design for a covered dish or a similar article as shown.

ALFRED JOHN MEAKIN.
